poration of Connecticut

Filed Nov. 17, 1959, Ser. No. 58,377

Term of patent 14 years

(Cl. D54—12)

FIG. 1

FIG. 2

FIG. 3

FIG. 4

FIG. 5

Fig. 1 is a front elevational view of a spoon showing my new design;

Fig. 2 is a rear elevational view thereof;

Fig. 3 is an edge elevational view thereof;

Fig. 4 is a cross-sectional view, on an enlarged scale, taken at line 4—4 of Fig. 1;

Fig. 5 is a cross-sectional view, on an enlarged scale, taken at line 5—5 of Fig. 1; and

Fig. 6 is an enlarged fragmentary view taken above the dot-dash line in Fig. 1.

The characteristic feature of my design resides in the specific floral decoration on the handle tip which presents a three dimensional effect with the floral opening on the face and the underside of the blossom showing on the back in association with the raised beads on the edges of the handle, all as shown.

I claim:

The ornamental design for a spoon or similar article, substantially as shown and described.
